UNITED STATES PATENT OFFICE.

CHARLES EUGEN LANCELOT BROWN, OF ZURICH, ASSIGNOR TO THE
WERKZEUG UND MASCHINENFABRIK OERLIKON, OF OERLIKON,
SWITZERLAND.

DYNAMO AND MOTOR.

SPECIFICATION forming part of Letters Patent No. 386,685, dated July 24, 1888.

Application filed November 9, 1886. Serial No. 218,386. (No model.)

To all whom it may concern:

Be it known that I, CHARLES EUGEN LAN-
CELOT BROWN, a citizen of England, residing
at Zurich, in the canton of Zurich, Switzer-
land, have invented certain new and useful
5 Improvements in Electric Generators and Mo-
tors; and I do hereby declare the following to
be a full, clear, and exact description of the
invention, such as will enable others skilled in
10 the art to which it appertains to make and
use the same, reference being had to the ac-
companying drawings, and to letters or figures
of reference marked thereon, which form a part
of this specification.

15 This new construction is shown by the an-
nexed drawings, in which—

Figure 1 represents the plan, Fig. 2 the ver-
tical longitudinal section. Fig. 3 the front
20 view, Fig. 4 an end view, and Fig. 5 a sec-
tional end view.

The dynamo is built in the following way:
The pole-piece K, with the lateral adjoined
pieces, directly forming the framing B, the
supports of the bearings C C', and the nipples
25 B' for the fastening of the machine, are com-
prised in one single piece of casting. The
cores of the magnets are incased in the pole-
piece K and fastened with the screws a a'.
The heads of the cores bear the pole-piece L,
30 to which they can be fastened in the same
way as in the lower pole-piece, or the pole-
piece sits flat on the cores and is fastened by
the screws b b', as shown in Fig. 3.

For lifting off the pole-piece L and to facili-
35 tate the conveyance of the machine the pole-
piece L is provided with an iron bow, M,
placed in it while it is cast.

In order to facilitate the winding of the coils
A A', the exciting-wire is coiled upon a cy-
40 lindrical casing made of metal or an insulating
material, and the whole slid over the magnetic
cores. The flanges retaining the coils are
made of wood or vulcanized or other fiber.
The cap-pieces of the plumber-blocks C" C' are
45 at the same time the grease-chambers, con-
taining both a liquid and a solid lubricant.
The axle-bearings are so disposed that the
dropping oil will be collected and led into the
drip-chambers D D' in the bearing-supports

C C', wherefrom it can be let off by a cock 50
placed at p p'.

The bearing on the side of the collector J is
provided with a groove, n, serving as guide to
the brush-bridge E. This consists of a collar
made of two parts, e e', which are held to- 55
gether by the screws d d'. By this means the
brush-bridge can be turned, but is not mova-
ble in the direction of the axis.

On the arms of the bridge, insulated plates
e e' are screwed, in which bear the spindles 60
for the brush-holders and connectors for the
current-conductors.

F refers to the steel armature-shaft; II, the
armature-iron to hold the coils and plates; J,
the collector or commutator, and G the driv- 65
ing-pulley.

The armature-iron is formed of thin insu-
lated rings f, made of charcoal-plates. They
are kept together and made fast to the shaft
by the bronze wheel N, and have grooves cor- 70
responding to the arms of the wheel to prevent
their twisting. They are compressed by the
bronze plates g g', the ribs h of which fit into
corresponding grooves in the wheel.

The disks or rings f are perforated with 75
holes f near their periphery, as shown in Fig.
4, in which holes the insulated copper wires k,
exposed to the inducing action, are pushed.
By this device the resistance which the mag-
netism has to overcome in passing from the 80
magnets to the armature is reduced to a mini-
mum, and obviates the necessity for fastening
of the wires of the armature to protect them
against the effect of the centrifugal force.
The single horseshoe-shaped wires are pushed 85
into the ring from the side of the pulley. The
projecting extremities on the other side are
connected by the lamels i to the collector J,
and with themselves to a closed circuit simi-
lar to the Pacinotti-Gramme ring arrange- 90
ment.

The composition of the collector is visible
in the drawings. The single lamels i are made
of phosphor-bronze. The insulation of the
single parts is produced by mica or asbestos. 95

The spokes of the pulley are shaped like the
vanes of a ventilator. The air, according to
the position of the vanes, is sucked through

the pulley and expelled through the apertures $x x$, or sucked through these latter and expelled through the pulley. To increase the ventilation, interstices y may be left open in the iron of the armature.

The pulley and collector can either be keyed directly on the shaft, or the nave of the bronze wheel may be lengthened and the above parts fastened to these projections. Fig. 2 represents the collector keyed directly to the shaft, while the pulley is fastened to the prolonged nave of the bronze wheel.

I claim in electric generators and motors—

1. The combination, with the brush-bridge 15 E, comprising the two parts $c c'$ and screws $d d'$, of the grooved bearing n , for said brush-bridge, and the insulated plate $e e'$, in the ends of which bear the spindles for the brush-hold-

ers and connectors for the current-conductors, substantially as set forth.

2. The herein-described armature, comprising the wheel N, the compressing-plates $g g'$, having ribs fitting grooves of said wheel, and the insulated rings f , held together by said wheel, substantially as set forth.

3. The combination, with the shaft F and the collector J, of the wheel N, the plates $g g'$, the insulated rings f , the horseshoe-shaped wires k , and the lamels i , substantially as set forth.

In testimony whereof I affix my signature in presence of two witnesses.

CHARLES EUGEN LANCELOT BROWN.

Witnesses:

JULIUS A. BOURRY,
WILLIAM SCHNEIDER.
